ARTIFICIAL LIMB

Charles Franklin Clack, Mineola, N. Y., assignor
of two-thirds to Henry J. Corsette and Charles
S. Bennington, Jr., both of Hempstead, N. Y.

Application June 19, 1937, Serial No. 149,227

15 Claims. (Cl. 3-2)

The invention relates generally to artificial limbs, or more particularly to artificial members of the so called hip-controlled type in which the limbs are wholly supported and controlled from the hips, and primarily seeks to provide a novel form of supporting and controlling means capable of very efficiently controlling the walking functions and of being worn with a greater sense of comfort and security than has heretofore been enjoyed.

Limbs of the type stated now in general use employ pelvic belts which encircle the body in the pelvic region, usually below the iliac crests and above the great trochanter, together with means for securing the belt to the thigh section of the limb and for connecting the belt with control devices within the limb. In order to obtain the desired feeling of security and confidence of control, limb users draw their belts very tightly about the pelvic region. Some wearers experience discomfort and even injury in forcing themselves to wear belting which traverse the abdominal region, and even those who can normally wear such belts without discomfort find it injurious to wear belts drawn too tightly. Moreover, in the at present known belts, if the belting is drawn tightly enough to satisfy standing and walking conditions, it will sometimes be found too tight in the sitting posture, and vice versa. The remedying of this condition constitutes one of the principal objects of my present invention.

Among the objects of the invention is to provide a limb supporting and controlling belt devoid of any abdomen traversing portion and in which provision is made for self-adjusting the supporting equipment to all conditions of use.

Another object of the invention is to provide a novel means for yieldably attaching the belt to the limb.

Another object of the invention is to provide a novel form of limb supporting and controlling belt in which is included means for yieldably gripping the person of a wearer.

Another object of the invention is to provide a novel means for adjusting the relation of the belt parts upon the person of a wearer.

Another object of the invention is to form the belt of a plurality of yieldably connected, partially rigid sections terminating at each side short of the abdominal region of a wearer, and to provide a novel encasement for said sections.

Another object of the invention is to provide a supporting belt including anterior and posterior sections yieldably urged toward one another to

yieldably grip the person of a wearer, and a control strap connected to the belt sections and to limb shank controlling devices in such a manner as to control the walking function during walking, and to relax the yieldable grip of the anterior belt section on the person of the wearer while maintaining the posterior section in back supporting relation during sitting.

With the above and other objects in view that will hereinafter appear, the nature of the invention will be more clearly understood by following the description, the appended claims, and the several views illustrated in the accompanying drawings.

15 In the drawings:

Figure 1 is a front elevation illustrating the invention in use.

Figure 2 is a detail side elevation illustrating the invention, parts being in section.

20 Figure 3 is a detail perspective view of the belt proper unsheathed.

Figure 4 is a detail perspective view of a form of sheath for the belt proper, parts being broken away and in section.

25 Figure 5 is a detail perspective view of the belt side opposite the side of amputation.

Figure 6 is a view similar to Figure 5 showing a modified form of belt extension joint employing a ratchet lock.

30 Figure 7 is a somewhat diagrammatic plan view of the belt.

Figure 8 is a vertical cross section taken on the line 8-8 on Figure 5.

Figure 9 is a vertical cross section taken on the 35 line 9-9 on Figure 6.

Figure 10 is a detail perspective view showing a modified form of belt embodying modified elastic and pivot structures.

40 Figure 11 is an enlarged detail horizontal section taken on the line 11-11 on Figure 2.

Figure 12 is a vertical cross section of the rubber pivot mounting block.

Figure 13 is a horizontal section of the rubber pivot mounting block.

45 Figure 14 is a detail vertical section taken on the line 14-14 on Figure 2.

Figure 15 is a detail plan view of a modified form of the invention in which the anterior and posterior belt sections are separately sheathed and provided with a bridge portion.

50 Figure 16 is a somewhat diagrammatic side elevation showing the position assumed by the parts during a sitting posture.

In the drawings, in which like numerals of reference indicate like parts in all of the figures,

I have shown the invention applied to an artificial limb embodying the usual thigh section 5, shank section 6 and foot section 7, the sections 5 and 6 being articulated or pivotally connected by any acceptable form of knee joint 8. The knee equipment includes the usual check 9 and shank control crank 10.

My improved limb supporting and controlling belt is generally designated 11 and preferably is composed of three sections of spring steel, duraluminum or other suitable material shaped to engage at the sides and back only of the pelvic region of a wearer, thereby being devoid of any portion traversing or pressing the central abdominal region. The three sections are designated 12, 13 and 14, the first two being herein-after termed anterior and posterior sections, and the latter the side section or side engaging portion. The sections 12 and 13 are shaped and intended to yieldably grip between them the hip portion of a wearer at the side of amputation and are disposed in end to end relation with the ends spaced for a purpose that will soon be explained. The posterior section 13 is extended across the back and is telescopically overlapped by the side section 14 which is shaped to fit against the good side of the wearer, or the side opposite the side of amputation.

The belt is applied to the pelvic region below the iliac crests and above the great trochanter, and the relation of the belt sections is diagrammatically shown in Figure 7.

Secured to each of the opposed ends of the sections 12 and 13, by rivets, welding, sleeve screws or any other suitable securing devices 15, is a link member 16. These spaced links depend from the belt approximately to the level of the femur pivot or natural hip axis, and they are shaped to converge and also to extend a bit laterally of the vertical plane in which they are mounted. At their lower ends the links are connected, by spaced pivots 17, to a mounting block 18 which is in turn yieldably secured to the thigh section 5 of the limb to be supported and controlled.

The block 18 is removably receivable in a metal socket or cup 19 fitted into a recess in the outer face of the thigh section 5. A bore passes through the recessed wall of the thigh section, and is bushed as at 20, and this bore communicates with an inside face recess in the thigh section which is fitted with another reinforcing metal cup or socket member 21. A rubber cushion block 22 is mounted in the cup 19 beneath the block 18, and a rubber cushion block 23 is mounted in the cup 21 beneath the flat head 24 of a securing bolt 25 which projects through the bushed bore, the cushion blocks, and the block 18. The parts are securely, but yieldably clamped together by a flat nut 26 which is notched at its periphery to receive the lock dog 27 screw secured upon the block 18. This rubber block mounting of the metal parts permits a degree of flexibility or yield sufficient to prevent crystallization and breakage of parts. The rubber blocks preferably are thickest at their central portions and are feathered slightly toward their edges. See Figures 2, 11, 12 and 13.

A mounting hook 28 is formed integrally with each link or secured in any approved manner to form an end extension from each of the opposed ends of the anterior, posterior sections 12, 13 and rubber bands 29 or other elastic or spring devices are attached to the hooks and serve to yieldably and constantly urge the section ends toward each other to cause said sections to yieldably grip the

person of a wearer therebetween as shown in Figures 2 and 7.

In order better to fit the belt to a wearer, and to provide for lateral or side to side gripping of the person of the wearer, as well as the anterior-posterior gripping previously referred to, the side section 14 of the belt is mounted telescopically upon the back portion of the posterior section 13. This may be accomplished by reducing the size of the side section end as at 30 and slidably projecting it through receiving cleats or straps 31 mounted on the overlapped posterior section end. An elastic strap 32 may be secured as at 33 to the back portion of the posterior section and removably and adjustably connected to the side section as at 34. With this equipment the sections 13 and 14 will be constantly urged in side to side body gripping relation and the section 14 can be wholly removed with great facility. In Figure 7 of the drawings the anterior-posterior gripping of the person of a wearer of the belt is indicated by the arrows AP, and the side to side gripping by the arrows SS.

A buttock engaging pad 35 depends from the belt at the side of amputation and preferably is yieldably and removably secured to the posterior belt section 13 as indicated at 36. See Figures 2 and 14. This pad materially adds to the sense of comfort and security enjoyed by wearers of my improved belt.

The anterior belt section 12 is provided with a button 37 or other suitable anchoring medium, and a similar medium 38 is affixed to the posterior section. A control strap 39 including an elastic section is included as a part of my improved supporting and controlling equipment and has its bight disposed beneath the control crank 10 and its free ends respectively connected to the anchoring media 37 and 38 so that the movement of the shank section 6 of the limb can be suitably controlled from the hips of the wearer.

When a person assumes a setting posture, the muscles about the pelvic region relax and the buttocks and other fleshy parts about the mid section spread in a manner rendering a tight belt or similar restriction quite uncomfortable, if not injurious. In my improved supporting belt the yieldably connected sections readily spread to accommodate this form of body expansion and all discomfort is avoided. Moreover, when the body parts spread during the assuming of the sitting posture the length of the control strap 39, adjusted for walking control, is caused by the body spread to exert a pull at its anchorage to the anterior belt section 12, serving to pull this section bodily forward in a manner definitely freeing pressure against the person of the wearer at this point. See Figures 7 and 16. This pulling forward of the belt section 12 also acts through the yieldable connection 29 to yieldably pull the posterior section 13 and the pad 35 carried thereby against the buttock and back portion of the wearer in a manner for very effectively bracing the wearer at the back during sitting intervals.

The belt sections may be sheathed in any approved manner to protect a wearer from direct contact. A conventional way of covering belt portions is by use of padded leather coverings laced or otherwise secured in place. I prefer to sheath my belt sections with individual sheaths, one for each of the three individual sections. These sheaths preferably are formed of thin tubular rubber portions 40 having a thick-

ened body opposing or inner portion 41 of sponge rubber molded thereon as shown in Figure 4.

In Figure 6 I have illustrated a modified means for telescopically connecting the belt sections 13 and 14. The reduced edges of the section 14 may be provided with ratchet teeth 42 to be engaged by spring dogs 43 carried by the back portion of the section 13. The dogs 43 will serve to hold any adjustment of relation of the belt sections 13 and 14, and release button equipment 44 may be utilized to release the locked relation and permit adjustment or separation of the parts.

Instead of rubber bands 29 or spring devices for yieldably urging the belt sections 12 and 13 together I may employ an elastic strap 45 and attach one end thereof to the posterior anchoring button 38 and the other end, adjustably, to the anterior button 37, so that the intermediate portion will bridge the space between the opposed ends of the belt section. See Figure 10. In this same view I have shown another modification of the invention in which both depending links 16 are pivoted to the block 18 at a single point 46 instead of providing individual, spaced pivots as hereinbefore described.

If found desirable, one of the belt sections 12 or 13 may be extended across the space between the section ends, as indicated at 47 in Figure 15, and permitted to telescope into the sheathing of the companion section. This equipment will effectually overcome any tendency of the person of a wearer to project and be pinched between the opposed ends of the sections.

Obviously other modifications of the structural details of my improved equipment may be made without departing from the scope of the invention as pointed out in the appended claims.

What I claim is:

1. An artificial limb supporting belt including anterior and posterior independently movable sections and shaped of semi-rigid material to provide portions adapted to engage at the back and sides of a wearer and terminating short of continuity across the front so as to be devoid of any abdomen traversing portion, means urging said sections toward each other for yieldably gripping the person of a wearer, and means depending from the belt for supporting an artificial limb.

2. An artificial limb supporting belt including independently movable, rigid, form-retaining anterior and posterior sections, a buttock pad fixedly connected to and depending from the posterior section, means urging said sections toward each other for yieldably gripping the person of a wearer, and means depending from the belt for supporting an artificial limb.

3. In an artificial limb, a thigh section, a shank section, means articulating the limb sections and including a shank section movement controlling crank, a supporting belt including independently movable, rigid, form-retaining anterior and posterior sections, means for pivotally connecting the belt sections to the thigh section, means connecting the anterior and posterior sections together and urging them toward each other for yieldably gripping the person of a wearer, and a control strap looped beneath the crank and having its free ends connected respectively to the anterior and posterior sections.

4. In an artificial limb, a thigh section, a shank section, means articulating the limb sections and including a shank section movement controlling crank, a supporting belt including in-

dependently movable, rigid, form-retaining anterior and posterior sections, means for pivotally connecting the belt sections to the thigh section, means connecting the anterior and posterior sections together and urging them toward each other for yieldably gripping the person of a wearer, said belt also including a side engaging portion extensibly connected to said posterior sections, means for controlling the degree of extension of said portion, and a control strap looped beneath the crank and having its free ends connected respectively to the anterior and posterior sections.

5. In an artificial limb, a thigh section, a shank section, means articulating the limb sections and including a shank section movement controlling crank, a supporting belt including independently movable, rigid, form-retaining anterior and posterior sections, means for pivotally connecting the belt sections to the thigh section, means connecting the anterior and posterior sections together and urging them toward each other for yieldably gripping the person of a wearer, said belt also including a side engaging portion extensibly connected to said posterior section, means for yieldably resisting extension movement between said portion and the posterior section, and a control strap looped beneath the crank and having its free ends connected respectively to the anterior and posterior sections.

6. In an artificial limb, a thigh section, a shank section, means articulating the limb sections and including a shank section movement controlling crank, a supporting belt including anterior and posterior sections, means for pivotally connecting the belt sections to the thigh section, means for urging the belt sections toward each other for yieldably gripping the person of a wearer, said belt also including a side engaging portion extensibly connected to said posterior section, said portion and said anterior section terminating in spaced relation so that the belt is devoid of any abdomen traversing portion, and a control strap looped beneath the crank and having its free ends connected respectively to the anterior and posterior sections.

7. In an artificial limb, articulated thigh and shank sections, a supporting belt including anterior and posterior sections presenting ends opposed in spaced relation, links depending from said ends and pivotally connected to said thigh section, and means interposed between said ends to yieldably draw them together and cause said sections to grip the person of a wearer.

8. In an artificial limb, articulated thigh and shank sections, a supporting belt including anterior and posterior sections presenting ends opposed in spaced relation, links depending from said ends and pivotally connected to said thigh section, and means interposed between said ends to yieldably draw them together and cause said sections to grip the person of a wearer, said belt also including a side engaging portion extensibly connected to said posterior section, and means for controlling the degree of extension of said portion.

9. In an artificial limb, a shank section, a thigh section, means articulating the limb sections and including a shank section movement controlling crank, a supporting belt including anterior and posterior sections presenting ends opposed in spaced relation, links depending from said ends and pivotally connected to said thigh section, means interposed between said ends to yieldably draw them together and cause said

sections to grip the person of a wearer, and a control strap looped beneath the crank and having its free ends connected respectively to the anterior and posterior sections.

10. In an artificial limb articulated thigh and shank sections, a supporting belt including anterior and posterior sections presenting ends opposed in spaced relation, links depending from said ends and pivotally connected to said thigh section, means interposed between said ends to yieldably draw them together and cause said sections to grip the person of a wearer, and means bridging the space between said opposed ends to prevent protrusion of the person of a wearer between said ends.

11. In an artificial limb, articulated thigh and shank sections, a supporting belt including anterior and posterior sections presenting ends opposed in spaced relation, links depending from said ends and pivotally connected to said thigh section, means interposed between said ends to yieldably draw them together and cause said sections to grip the person of a wearer, individual sheathing for said sections, and an extension from one said section telescopically engaging the sheathing of the other section and serving to bridge the space between the opposed section ends and prevent protrusion of the person of a wearer between said ends.

12. In an artificial limb, articulated thigh and shank sections, a supporting belt including anterior and posterior sections presenting ends opposed in spaced relation, links depending from said ends and pivotally connected to said thigh section, said pivotal connection including a resilient material inlay permitting a degree of free lateral movement tending to prevent crystallization of the pivoted parts, and means interposed between said ends to yieldably draw them to- 40

gether and cause said sections to grip the person of a wearer.

13. In an artificial limb, articulated thigh and shank sections, a supporting belt including anterior and posterior sections presenting ends opposed in spaced relation, a pivot member secured to and projecting upwardly from said thigh section, links depending from said ends and individually-pivotally connected in spaced relation to said pivot member, and means interposed between said ends to yieldably draw them together and cause said sections to grip the person of a wearer.

14. In an artificial limb, articulated thigh and shank sections, said shank section including a control crank, a supporting belt including anterior and posterior sections, means for pivotally connecting the belt sections to the thigh section, means for urging the belt sections toward each other for yieldably gripping the person of a wearer, and a control strap having a bight engaging said crank and its free ends respectively connected to said anterior and posterior sections and effective during a sitting posture to move the anterior section to relieve body pressure and to yieldably hold the posterior section in back bracing relation.

15. In an artificial limb, a thigh section presenting inner and outer faces, a supporting belt including a depending arm, a pivot block to which said arm is pivotally connected, said thigh section having registering recesses in its inner and outer faces, a resilient block mounted in each recess, said thigh section said pivot block and said resilient blocks having an aperture therethrough, and an anchoring bolt passing through said aperture and having a head lying in the inner recess and serving to yieldably secure the pivot block in the other recess.

CHARLES FRANKLIN CLACK.
